UNITED STATES PATENT OFFICE.

JOHN B. CHACE, OF SOUTH ATTLEBORO, MASSACHUSETTS.

BRAIDING MACHINE.

Application filed June 25, 1920. Serial No. 391,708.

To all whom it may concern:

Be it known that I, JOHN B. CHACE, a citizen of the United States, residing at South Attleboro, in the county of Bristol, 5 State of Massachusetts, have invented certain new and useful Improvements in Braiding Machines, of which the following is a specification.

My invention relates to improvements in 10 braiding machines for fabricating braided cords and the like.

One object of the invention is to provide an improved braiding machine capable of increased speed of operation and greater 15 productive capacity.

Another object of the invention is to provide for the use of larger bobbins of yarn on the bobbin-carriers of the machine whereby to reduce the number of stoppages required for replenishing the yarn supply.

Another object of the invention is to relieve the friction and lessen the wear on the running parts of the machine to provide for greater durability and reduce the cost 25 of repairs.

Further objects of the improvement will appear from the description of the embodiment of the invention set forth in the following specification which is illustrated by 30 the accompanying drawings. In the drawings:

Fig. 1 is a plan view of a section of the deck of a braiding machine showing my improvements applied thereto;

Fig. 2, a vertical sectional view taken through the deck of the machine on the line A—A of Fig. 1, and illustrating the bobbin-carriers which travel in the grooves or tracks in the deck;

Fig. 3, a similar sectional view taken in a circular plane on the line B—B of Fig. 1; and

Fig. 4, an enlarged side elevation of one of the bobbin-carriers of my improved machine.

My improvements are directed to a common type of braider having one or more horizontal decks or track-plates provided with circuitous grooves or guideways in 50 which the bobbin-carriers are traveled around the axis of the machine. There are

usually two guideways in the deck or track-plate, leading in a tortuous or sinuous course around the central axis of the machine and crossing each other at regular 55 intervals. Two sets of bobbin-carriers are traveled in opposite directions in the guideways to cause them to pass inwardly and outwardly around each other to interlace their strands in accordance with the well 60 known method of a maypole dance. The present invention relates to an improved arrangement of the guiding-means for the carriers and consists particularly in a plurality of auxiliary runners, rollers or 65 guiding-shoes on each carrier adapted to engage with the track-grooves in the deck. In the embodiment of the invention herein shown the track-plate is constructed with a relatively deep groove or guideway, the upper 70 portion of which is engaged by the main runners of the carrier, while the lower portion of the groove or guideway is adapted to be engaged by auxiliary studs or rollers arranged fore and aft of the main runner 75 on the carrier.

Referring first to Fig. 1 of the drawings I have here illustrated a section of approximately one-quarter of the full circumference of the deck or track-plate, indicated 80 in general by the reference character 2; it being understood that the deck consists of a complete ring or circular plate. The deck 2 comprises an inner ring 3 having equidistant star-points 4 whose outer edges 85 form one side of the guiding tracks 5 and 6 in which the runners or shoes of the carriers slide. Surrounding the inner ring 3, outwardly therebeyond, is an outer ring 7 formed with inwardly projecting points 8 90 which are arranged radially opposite the points 4. Arranged centrally within the spaces between the points 4 and 8 of the rings 3 and 7 are irregularly-shaped plates 9, usually called quoits. The quoits 9 have 95 their edges lying contiguous to and spaced slightly apart from the scalloped edges of the rings 3 and 7 whereby to provide the sinuous grooves or guideways 5 and 6 which intersect at the crossing points 10. The 100 several sections 3, 7 and 9 of the deck or track-plate 2 are arranged in a horizontal

plane, being supported on the upstanding webs 11 of a lower frame-member 12, see Fig. 2. The inner and outer deck sections or rings 3 and 7 and the quoits 9 are held 5 in place on the frame 12 by means of vertical bolts 13 carrying nuts 14 at their ends, see also Fig. 3. The bolts 13 extend through central hubs 15 on the under side of the quoits 9, and the plate sections or rings 3 and 7 have ribs 16 resting on the webs 11 of the frame 12, see Fig. 2. Held between the hubs 15 on the quoits 9 and raised bosses 17 on the frame 12 are cylindrical sleeves or bushings 18 which serve as bearings for the 10 usual horn-gears 20 which propel the carriers 25 of the braider through the grooves 5 and 6. The bushings 18 are formed with lugs 19 projecting from their ends and engaging slots 22 in the hubs 15 and 17 to 15 locate the bushings in position and prevent them from turning, see Fig. 3. The horn-gears 20 are formed with hubs 23 journaled on the bushings 18, and are arranged with their teeth 21 intermeshing as shown in Fig. 20 25. In this way a circular train of gearing is provided extending circumferentially of the central axis of the machine and adapted to be driven from an outer gear which receives its motion from the power-actuated 30 driving-shaft of the machine. The driving connections for the gears 20 may be of any well known arrangement and are not herein shown since they have no relation to the present improvement. Suffice it to state 35 that the alternate gears 20 of the circular train are rotated in opposite directions to propel the carriers 25 through their guideways in the manner as well known in the art.

40 The gears 20 carry superimposed, circular plates or disks 26 formed with radial slots 27, see Fig. 1, which engage the horns 28 projecting from the under sides of the carriers 25. Referring to Fig. 3, the edges of 45 the disks 26 overlap at the points where the teeth 21 of the gears 20 intermesh and as the adjacent gears turn in opposite directions the horn 28 on the carrier passes from one slot 27 to another to transfer the carrier progressively through all of the gears.

50 As before indicated the present improvement relates particularly to the means for guiding the carriers through the grooves or guideways of the track-plate 2. Referring 55 to Fig. 4, the carrier 25 for the yarn-bobbin B is constructed with a horizontal base 30 for supporting the bobbin-spindle 31. In my present improved structure the base 30 may consist of a flat plate which is preferably formed with a pointed-prow at its leading end and a rounded rearward end whereby to adapt it to clear the other carriers as it passes thereby. Beneath the base-plate 30 is a correspondingly-formed guide-plate 32 which travels below the track-plate 60 65 2 and bears against its ribbed under side to steady the carrier during its movement in the guideways of the deck. The upper and lower plates 30 and 32 are secured in spaced relation by means of vertical studs 33 and 34. As shown in Fig. 4 the forward stud 33 is reduced at its ends and riveted through the two plates 30 and 32 to form a rigid strut therebetween. The rearward stud 34 is reduced in diameter at its lower 70 75 end and riveted through the bottom plate 32; while its upper end is extended in the bobbin-spindle 31 which is driven through a hub 35 on the top of the plate 30. Adapted to turn on the spindle 31 above the hub 80 85 35 is a sleeve 36 for receiving the wooden or paper bobbin B which carries the supply of yarn Y, indicated by dot-and-dash lines in Fig. 4. The turning of the bobbin B with its sleeve 36 is controlled by a pawl 37 engaging the ratchet-teeth on the head 38 of the bobbin. The pawl 37 is mounted on the lower end of a wire rod 39 which is formed with a loop 40 at its upper end encircling a vertical standard or bar 41 which rises 90 95 90 from the forward end of the base 30 of the carrier 25. Mounted to slide on the standard 41 is a tension-weight 42 having guiding slots 43 through which the yarn or thread y leads from the bobbin B. The strand or thread y passes up through a guide-eye 44 at the top of the standard 41, and as it is drawn off from the bobbin B it will have a tendency to lift the tension-weight 42. As the weight 42 rises against 100 105 the loop 40 on the rod 39 it raises the pawl 37 away from the ratchet 38 on the bobbin B to allow the latter to rotate to deliver the yarn in lengths as required by the braiding operation.

110 The above described arrangement of the mechanism of the braider is in accordance with the general construction of this common type of machine and my present improvements, which are related to the guiding-means for the bobbin-carriers 25, will now be described. Usually the base of the bobbin-carrier is constructed in a single piece with a vertical shoe or runner of substantially oblong shape which travels in the 115 grooves in the track-plates and upper and lower horizontal rims or flanges which engage the top and bottom edges of the grooves. The runner or guiding-shoe must be of sufficient length to adapt it to span the 120 crossovers 10 in the grooves or tracks 5 and 6; and in order that the runners may pass around the curves in the track the grooves are cut away or widened at these points. The usual practice is to cut away the curved 125 edges of the quoits 9, as indicated at X in Fig. 1, to allow the runners to take the curves, and with such a construction the runner or shoe on the carrier will have a loose and more or less "sloppy" fit in the 130

track. This tends to allow an uneven or "wobbly" action of the carrier as it slides in the track or guideway and has the effect of materially reducing the speed at which 5 the carriers may be revolved around the machine. Furthermore, the play of the carrier shoes or runners in the track causes excessive friction and wear on the parts with the result that frequent repairs and 10 placements are necessary. To correct this condition and remedy the defects in the construction of previous types of machines I have devised a track or guiding arrangement which insures a smooth even movement 15 of the carrier in its track, with a minimum of friction between the engaging parts, with the result that the machine may be operated at a much higher speed and with materially less wear and strain on its mechanism. 20

As before described my improved carrier 25 is constructed with upper and lower flanges or plates 30 and 32 which serve the same purpose as the top and bottom flanges 25 of the usual form of carrier and on the bottom of the plate 30 is a shoe or runner 45. It is to be noted, however, that the plates 30 and 32 are spaced at a greater distance apart than in the usual construction, and 30 it will be observed that the track-plate 2 is correspondingly thickened by means of the hubs 15 and webs 16 shown in Figs. 2 and 3 and previously described. It is also noted that the vertical runner 45 which projects 35 down from the bottom of the top plate or base 30 of the carrier is of relatively slight depth so that it will engage with the grooves 5 and 6 of the track-plate 2 only along the upper edges thereof. That is to say the 40 main shoe or runner 45, which is of rectangular shape in cross-section, as shown in Figs. 1 and 2, does not extend from the top plate 30 to the lower plate 32 as in the usual construction, but only about one- 45 third the distance between the plates, see Fig. 4.

It has been explained that the plates 30 and 32 are fastened together in spaced relation by means of the vertical studs 33 and 50 34 and these studs serve for a further purpose, that of providing auxiliary guiding-means or runners for traveling in the track-grooves 5 and 6. The bodies of the studs 33 and 34 may be made of a diameter to 55 adapt them to fit freely between the sides of the grooves 5 and 6 to engage therewith, but in accordance with the preferred construction shown in Fig. 4 I employ the studs 33 and 34 as journals for the rollers 46 which are adapted to turn freely thereon. The rollers 46 are adapted to be received 60 within the grooves 5 and 6 of the track-plate 2 to travel along the sides thereof with a free rolling motion whereby to reduce the 65 friction and wear on the parts.

Referring to Fig. 1 of the drawings it will be seen that the main runner or shoe 45 travels in the upper part of the grooves 5 and 6 and serves as a sort of guide or pilot to direct the carriers through the crossings 70 10 without allowing them to be diverted from their normal direction of travel, see dash lines in Fig. 1. The studs 33 and 34, with their rollers 46, form the auxiliary guiding-means for the carriers and, being arranged fore and aft of the main or pilot runner 45, they take practically all of the thrust against the sides of the track-grooves 75 5 and 6 and thus tend to greatly relieve the friction and wear between the engaging surfaces. It will be noted by reference to Figs. 80 1 and 2 that the quoits 9 are cut away on their curved sides only at their upper edges, that is at the top of the track-grooves 5 and 6. Stated another way, it will be seen that 85 the track-grooves are of uniform width throughout their main portions and are only widened at their top sides to accommodate the pilot or guiding shoe 45 as it travels around the sharp turns or bends in 90 the track. It will thus be apparent that since the guiding-rollers 46 travel in the lower portion of the track they will direct the carriers in a truer course and will slide through the track-grooves with a smoother 95 evener motion, without play or vibration. The rollers 46 also tend to guide the carriers around the turns of the track with an easier action and thus reduce strain and wear on the parts. For these reasons the carriers 100 may be traveled through the tracks at a much faster speed, with less resistance and wear, and hence the speed of operation of the braider will be materially increased, with a corresponding increase in its rate of 105 production.

It is noted that the bobbin B is mounted on the trailing end of the carrier in axial alignment with the rear guiding stud 34. Through this arrangement the bobbin will 110 be traveled concentrically with respect to the outer and inner curves of the tracks 5 and 6 whereby two bobbins will pass each other at the maximum distance apart. That is to say, one bobbin passing at one side of 115 the quoit 9 will be at the maximum distance from the other bobbin passing on the opposite side of the quoit so as to provide more clearance for the bobbins. For this reason I have found it possible to employ much 120 larger bobbins on the carriers whereby the running time of the machine between stoppages for replenishment of the bobbins is increased. Stated briefly, by the use of larger bobbins the stoppages of the machine 125 for applying fresh bobbins or replenishing the supply of yarn are materially reduced and production thereby increased.

It will be observed from the above that my invention provides an improved braid- 130

ing machine adapted for increased speed of operation with greater productive capacity. By reducing the friction and wear on the mechanism I also provide for greater durability of the machine with a consequent saving in repairs and replacements.

Various modifications may be made in the construction and arrangement of the parts of my improved mechanism without departing from the spirit or scope of the invention; therefore, without limiting myself to the exact embodiment herein shown and described, what I claim is:

1. In a braiding machine, the combination 15 with a track-plate having grooved guideways, of bobbin-carriers for the yarn-supplies having main runners slidable in the guideways, and a plurality of auxiliary guiding-means on the carriers adapted to 20 engage the guideways at points fore and aft of the ends of the main runners.

2. In a braiding machine, the combination 25 with a track-plate having guiding-grooves, of a bobbin-carrier provided with a main shoe slidable in the grooves, and a plurality of auxiliary guiding studs on the carrier adapted to engage the grooves at points in advance and at the rear of the ends of the main shoe.

3. In a braiding machine, the combination 30 with a track-plate having track-grooves, of bobbin-carriers for the yarn-supplies provided with main runners engaging the grooves throughout a portion of their depth, 35 and a plurality of auxiliary guiding-means arranged fore and aft of the ends of the runners on the carriers adapted to engage with the track-grooves below the runners.

4. In a braiding machine, the combination 40 with a track-plate having sinuous track-grooves intersecting each other at intervals, of bobbin-carriers provided with longitudinal runners slidable in the grooves to direct the carriers through the crossovers thereof, and a plurality of auxiliary guiding-means on the carriages to engage the grooves at points fore and aft of the ends of the runners.

5. In a braiding machine, the combination 50 with a track-plate having track-grooves, of bobbin-carriers for the yarn-supplies provided with runners engaging the track-grooves along their upper edges, and a plurality of auxiliary guiding-means on the carriers adapted to engage the guiding-grooves throughout the full depth thereof.

6. In a braiding machine, the combination 60 with a track-plate having track-grooves, of bobbin-carriers for the yarn-supplies provided with guiding-means engaging the upper portion of the track-grooves, and a plurality of auxiliary guiding-means arranged fore and aft of the first-named guiding-means and adapted to engage with the track-grooves throughout the full depth thereof.

7. In a braiding machine, the combination with a track-plate having track-grooves, of 70 bobbin-carriers for the yarn-supplies provided with runners engaging the track-grooves throughout a portion of their depth only, and studs projecting below the carriers at points fore and aft of the runners and adapted to engage the track-grooves throughout their full depth.

8. In a braiding machine, the combination 75 with a track-plate having track-grooves, of bobbin-carriers for the yarn-supplies provided with runners projecting downwardly into the track-grooves throughout a portion of their depth only, studs projecting 80 downwardly from the carriers at points fore and aft of the runners, and rollers journaled on the studs to adapt them to engage the track-grooves below the runners.

9. In a braiding machine, the combination 85 of a track-plate having track-grooves, bobbin-carriers having upper and lower guiding-flanges slidable on the top and bottom of the track-plate in overlapping relation with the track-grooves, runners projecting 90 below the upper flanges to engage the track-grooves, and a plurality of auxiliary guiding-means extending between the flanges fore and aft of the runners and adapted to engage the track-grooves throughout their 95 full depth.

10. In a braiding machine, the combination of a track-plate having track-grooves, bobbin-carriers having upper and lower 100 guiding-flanges slidable on the top and bottom of the track-plate in overlapping relation with the track-grooves, runners projecting below the upper flanges to engage the upper portion of the track-grooves, vertical studs connecting the upper and lower 105 flanges at points fore and aft of the runners, and rollers journaled on the studs to adapt them to engage the sides of the track-grooves.

11. In a braiding machine, the combination 110 of a track-plate having track-grooves extending in a sinuous course and intersecting each other at intervals, bobbin-carriers having longitudinal runners engaging the upper portion of the track-grooves, and 115 auxiliary guiding-means arranged at the leading and trailing ends of the carriers and extending down into the track-grooves below the runners, the upper portion of the track-grooves being widened at the curves 120 to provide clearance for the runners but having a uniform width throughout their lower portion to adapt the auxiliary guiding-means to direct the carriers in a path coincident with the median vertical plane 125 of the track-grooves.

12. In a braiding machine, the combination 130 of a track-plate having track-grooves extending in a sinuous course and crossing each other at intervals, bobbin-carriers hav-

ing longitudinal runners engaging the upper portion of the track-grooves to guide the carriers through the crossovers, and rollers journalled on the carriers to engage the track-grooves at points below the runners, said track-grooves being cut away along their upper edges to provide clearance for the runners at the curves therein but having substantially uniform width at the bottom throughout their whole course. 10 In testimony whereof I affix my signature.

JOHN B. CHACE.
